UNITED STATES PATENT OFFICE.

VICTOR W. GIDEON AND PAUL O. UNGER, OF KANSAS CITY, MISSOURI, ASSIGNORS TO IRVING-PITT MANUFACTURING COMPANY, OF KANSAS CITY, MISSOURI, A CORPORATION OF MISSOURI.

POSTING DEVICE.

Application filed May 3, 1920. Serial No. 378,555.

To all whom it may concern:

Be it known that we, VICTOR W. GIDEON and PAUL O. UNGER, citizens of the United States, residing at Kansas City, in the county of Jackson and State of Missouri, have invented a certain new and useful Improvement in Posting Devices, of which the following is a specification.

Our invention relates to improvements in 10 posting devices adapted for use in loose leaf holding devices, such as posting trays. It relates particularly to a leaf upsetting device by which the upper edges of loose leaves held in the tray may be held in positions 15 adapted for the easy fingering and separation of the leaves in transferring them one by one from one pile to another.

The object of our invention is to provide a simple device of the kind described, which 20 is cheap to make, is not liable to get out of order, which is durable, and which can be readily placed in or removed from the tray with which it is to be used.

Our invention provides further an upsetting 25 device for the leaves which will automatically adjust itself in the tray, so as to remain in operative position, as the leaves are transferred from one pile to another in the tray.

30 The novel features of our invention are hereinafter fully described and claimed.

In the accompanying drawings which illustrate the preferred embodiment of our invention,

35 Fig. 1 is a vertical sectional view of our invention shown applied to a posting tray.

Fig. 2 is an under view, enlarged, of the upsetting device.

40 Fig. 3 is a vertical sectional view on the line 3—3 of Fig. 1.

Fig. 4 is a cross section on the line 4—4 of Fig. 2.

Fig. 5 is a horizontal sectional view of the upsetting device.

45 Fig. 6 is a reduced perspective view of the sheet upsetting device.

Similar reference characters designate similar parts in the different views.

1 designates the base of a posting tray between 50 two opposite sides of which extends a track, preferably comprising two parallel sections 2, the upper surfaces of which are, preferably rough or transversely corrugated so as to support and hold from lateral shift-

ing or slipping the lower edges of two piles 55 3 and 4 of loose leaves, which in the posting operation are disposed in an upwardly and outwardly inclined position, the piles inclining in opposite directions, as shown in Fig. 1.

The piles 3 and 4 are supported respectively in the inclined positions by two wings 5 respectively hinged to opposite sides of the base 1 at the ends of the track sections 2, so as to be swung from a closed vertical 60 position to the outwardly inclined position shown.

The leaf supporting and upsetting device comprises, preferably, a sheet metal body having end portions 6 in which are rotatably mounted two parallel longitudinal rods 7 each having mounted on its ends respectively rollers 8 which are adapted for travel on the adjacent track sections 2. The end portions 6 are disposed respectively adjacent 65 to the inner sides of the track sections 2 and serve to guide the upsetting device on the track.

The upsetting device is provided with two 70 downwardly diverging portions 9, which are steep enough to effect the functions for which they are designed, for example about 45 degrees inclination, and which, preferably extend longitudinally beyond the end portions 6. The portions 9 are adapted to support respectively the adjacent inner leaves of the piles 3 and 4, the inclination of the portions 9 serving to retain the upper edges of the inner leaves above the next 75 adjacent leaves at the outer sides thereof. By this construction the inner leaf of each pile 3 and 4 is above the next adjacent leaf, so that it can be readily fingered and detached from one pile to be transferred to the other pile in the posting operation.

Intermediate of the downwardly flaring portions 9 is a vertical longitudinal portion 10, which serves to retain the loose leaves 80 from accidental shifting from one inclined portion 9 to the other, and which also serves 85 as a guide in the transferring of the sheets from one pile to the other.

In the operation of the invention, the upsetting device is placed in the tray with the rollers 8 mounted on their respective track 90 sections 2. The leaves are then mounted in the tray with their lower edges resting on the track sections 2, and are transferred, as

posted from one pile 3 to the pile 4, the adjacent inner sheets of each pile having their lower edges resting on the adjacent inclined portion 9, as shown in Fig. 1. As the sheets 5 are lifted from the pile 3 and transferred to the pile 4, the inner sheets of the pile 3 are occasionally lifted a short distance, upon which the pressure of the sheets of the pile 4 will force the upsetting device along

10 the track toward the pile 3, the change in position being represented in solid and dotted lines in Fig. 1. As the inner sheets of pile 3 are lifted occasionally, as above stated, the upsetting device will travel 15 along, due to the pressure of the sheets of pile 4 which are resting on it, following which the lifted sheets are lowered on the adjacent inclined portion 9, thereby retaining the inner sheets of pile 3 in the upset 20 position, that is with the innermost sheets the highest, so that they can be readily separated one by one in the posting operation.

It will be obvious that the sheets may be transferred in the opposite direction, that is 25 from pile 4 to pile 3, if it is so desired. After the posting operation, the upsetting device may be removed and used in another tray, if desired.

Our improved device can be used with any 30 posting device in which the upsetting device is adapted for travel and in which the loose leaves may be held in two piles inclined apart.

We do not limit our invention to the structure 35 shown and described, as many modifications, within the scope of the appended claims, may be made without departing from the spirit of our invention:

What we claim is:—

40 1. In a posting device of the kind described, means for supporting leaves on their lower edges in two piles which incline upwardly away from each other, and loose leaf upsetting means having two downwardly diverging portions adapted to respectively support adjacent leaves of said piles, said upsetting means being adapted for travel on said leaf supporting means as leaves are transferred from one of said diverging portions to the other, substantially as set forth.

2. In a posting device of the kind described, means for supporting loose leaves on their lower edges in two piles which incline upwardly away from each other, and leaf upsetting means having two downwardly diverging portions adapted to respectively support adjacent leaves of said two piles, the upsetting means having roller 55 supporting means adapted for travel on said leaf supporting means as leaves are transferred from one of said diverging portions to the other, substantially as set forth.

3. In a posting device of the kind described, a tray having means for supporting

loose leaves in two piles which incline upwardly away from each other, the tray having a track adapted to support the lower edges of the leaves of said piles, and leaf upsetting means adapted for travel on said track and having two downwardly diverging portions adapted to respectively support the lower edges of adjacent leaves of said piles, substantially as set forth.

4. In a posting device of the kind described, a tray having two sides and a base provided with a track extending between the two sides and adapted to support the lower edges of loose leaves, the tray having two wings respectively hinged to said sides and adapted to swing from the upright to an upwardly and outwardly inclined position for respectively supporting two piles of leaves which incline away from each other, and means adapted for travel on said track for supporting adjacent leaves of said piles at different heights from the track, substantially as set forth.

5. In a posting device of the kind described, a tray having a base provided with a track extending between two sides and adapted to support the lower edges of loose leaves of two piles disposed in oppositely inclining positions, and a leaf upsetting means adapted for travel on said track and having two downwardly diverging portions adapted to respectively support the lower edges of adjacent leaves of said two piles and a vertical portion extending upwardly from the junction of said diverging portions, substantially as set forth.

6. In a posting device of the kind described, a means for holding loose leaves in two piles inclined away from each other and having a track adapted to support the lower edges of said leaves, and leaf-supporting means adapted for travel on said track and having an inclined portion adapted to support the lower edges of the inner leaves of one of said piles and a vertical portion extending upwardly from the upper end of said inclined portion, substantially as set forth.

7. In a posting device of the kind described, means for holding loose leaves in two piles inclined away from each other and having a track adapted to support the lower edges of said leaves, and leaf-upsetting means having a supporting roller adapted for travel on said track and having two downwardly diverging portions adapted to support adjacent leaves of said two piles, and a vertical portion extending upwardly from the junction of said diverging portions, substantially as set forth.

8. In a posting device of the kind described, a tray having a base provided with a track extending between two sides and adapted to support the lower edges of loose leaves, the tray having two outwardly in-

clined leaves extending upwardly respectively from said sides and adapted to respectively support two piles of said leaves which incline outwardly away from each other, and a leaf-upsetting device adapted for travel on said track and having two downwardly diverging portions adapted to respectively support the lower edges of adjacent leaves of said two piles, substantially 10 as set forth.

9. In a posting device of the kind described, a leaf supporting device having a carrying roller and two downwardly diverging portions adapted to support the lower 15 edges of loose leaves, and a vertical portion extending upwardly from the junction of

said diverging portions, substantially as set forth.

10. In a posting device of the kind described, a leaf supporting device having two 20 longitudinal downwardly diverging portions adapted to support the lower edges of loose leaves and a vertical portion extending upwardly from the junction of said diverging portions, and having carrying 25 rollers at opposite ends respectively, substantially as set forth.

In testimony whereof we have signed our names to this specification.

VICTOR W. GIDEON.
PAUL O. UNGER.
